CLAIM

The ornamental design for mouse with side gap, as shown and described.

DESCRIPTION

FIG. 1 is a perspective view of a mouse with side gap showing our new design;

FIG. 2 is a top plan view thereof;

FIG. 3 is a right side elevational view, the left side elevational view being a mirror image thereof;

FIG. 4 is a front elevational view thereof;

FIG. 5 is a rear elevational view thereof; and,

FIG. 6 is a bottom plan view thereof.

Phantom lining, where utilized, is for illustrative purposes only, and is not intended to limit the claimed component design to the features shown in phantom.
